UNITED STATES PATENT OFFICE.

JOSEPH A. ARSENAULT, OF BERLIN, NEW HAMPSHIRE.

SUBMARINE CHASER.

1,270,094.

Specification of Letters Patent. Patented June 18, 1918.

Application filed November 3, 1917. Serial No. 200,150.

To all whom it may concern:

Be it known that I, JOSEPH A. ARSENAULT, a citizen of the United States, residing at Berlin, in the county of Coos and

5 State of New Hampshire, have invented new and useful Improvements in Submarine Chasers, of which the following is a specification.

This invention relates to submarine vessels, and more particularly it consists of a plurality of searchlights directing their beams in various directions, together with glass-covered observation windows adjacent them. Details of my preferred construction are set forth in the following specification and shown in the drawings wherein:—

Figure 1 is a side elevation;

Fig. 2 is a general central vertical longitudinal section, partly in side elevation, 20 showing a practical arrangement of parts;

Fig. 3 is a horizontal section through the hull giving a plan view of the driving mechanism, and

Fig. 4 is a transverse section about on the 25 line 4—4 of Fig. 2.

The hull 1 of this submarine vessel will by preference be made of sheet metal plates riveted and welded edge to edge so as to be watertight, in transverse section it is circular or oval, and in longitudinal section it is of well known cigar shape with points at both ends. These points 2 are steel-covered and constitute rams or piercing punches adapted to be driven into the hull of the 30 enemy submarine, although of course they may be driven into the hull of any enemy ship which they could pierce. At its mid-length for a certain distance the hull is truly cylindrical, and its ends taper from the 35 cylindrical portion to the points or rams 2. Below each tapering end is a keel 3, and an opening therein moves the rudder 4. The steering mechanisms are not shown, but will of course be in duplicate and separate from 40 each other, as one rudder must be set fixedly at whichever is the forward end of the vessel while the other rudder is manipulated to steer the same. 5—5 are the submerging rudders, and 6 are the propellers. The driving mechanism therefor is not shown, but it must be such that the propellers may be rotated in either direction with equal speed at will. Ladders or stairways 7 lead upward through hatches 8 at the midlength and 55 give access to a deck at the top surrounded by a suitable rail 9. The hull is internally

equipped with suitable quarters for the crew, tanks for storage, receptacles for food and ammunition, and the motive elements and their driving means or bunkers or tanks 60 for their fuel. I prefer, as is usual with submarine vessels, to use gasoline engines when the vessel is at the surface and the hatch 8 and other air-openings are open, and electric motors when the vessel is submerged and the contained air is necessary 65 for the crew.

One important feature of my invention is the means for permitting the quick submergence of this submarine chaser at either 70 end, and while this feature is valuable in a chaser, it might also be valuable in a submarine boat and I do not wish to be limited as to its use. The present device being a double-ended vessel, the submerging means 75 are duplicated. At some little distance from the midlength of the hull toward each ram there is disposed a ballast tank 10 of considerable size, and pipes 11 open from it through the sides of the hull and contain 80 sea-cocks 12 which when opened admit water to the tank and cause this end of the vessel to be heavier and therefore to settle as is well understood. The tank may be later easily depleted of this water through 85 an outlet pipe 13 having a valve 14, by means of a pump 15. The structure of tanks 10 is shown in Fig. 4 and their relative position is shown in Fig. 2. These tanks each include an upper member the middle portion 90 of which provides a floor for the main chamber while the sides extend upwardly at 10' along sides of the hull, and are spaced therefrom, being deflected and secured at 10°. This formation of the tank walls increases the capacity of the tanks without 95 materially detracting from the available space within the main chamber.

With this construction, let us assume that the vessel is traveling on the surface and 100 partly submerged, and an enemy vessel is discovered ahead. The hatches 8 and other openings are immediately closed, the forward sea-cocks 12 opened, and water begins to run into the tank 10. This causes the fore 105 part of the vessel to soon become heavier than the after part, and the result is that the bow of the vessel is inclined rapidly downward so that as she is driven forward by her propellers she dives or submerges quickly. 110 In addition the horizontal rudders 5 will be set as usual with submarine vessels. The

purpose is to get the chaser quickly below the surface so that she can bring her ram into use on the submerged portion of the hull of an enemy vessel or on any part of the hull of an enemy submarine. In addition, it is possible that the vessel could be provided with torpedo tubes, but this detail is not illustrated herewith, as it forms no part of the present invention.

10 Another and extremely important feature of my invention is the means for discerning a wholly submerged enemy vessel, such as a submarine which may perchance lie on the bottom. Just forward and rearward of the 15 deck the hull is arched at its top as at 30 to produce headway for what I call the observation room, and this headway has a flat front wall 31. The latter is provided with an observation window 32, each side of the 20 arch with two similar windows 33 and the top of the arch with a window 34, making six observation openings in each headway arch. Contiguous to these several windows are strong searchlights 35 directing their 25 beams forward, laterally, and upward when properly manipulated from the interior by the handles 36 as illustrated. When the vessel is afloat these lights and windows are above the surface, but other lights 37 are mounted on the bow and stern just inside the 30 rams 2 and facing forward and aft, and still others 38 in channels 39 in the keel 3 and facing a beam. These searchlights 37 and 38 are always beneath the surface of the 35 water, although the observation takes place through side windows 40 in the hull when the vessel is awash or through the windows 32 or 33 when it is afloat. Details of the construction of the searchlights are not essential 40 to this specification, but I prefer that they be strong electric lights, and they may of course be controlled by switches within reach of the operator on the interior.

Thus is produced a submarine chaser having rams at both ends, means for quick submergence when occasion arises, and searchlights on all sides projecting beams of light in all directions and serving as "eyes" with which the navigator may constantly search 50 the surrounding water for submerged enemy vessels. Having discovered one, he may quickly manipulate his little craft by descending or rising at will, steer it toward

the enemy, and ram the hull of the vessel with one of his steel points 2—in fact his 55 ram might be used successfully on the hull of any enemy craft, and of course he could use torpedoes if his vessel were provided with them. At the same time his defense lies in his small size, rapidity of movement, 60 ready submergence, and the fact that most of his work is done when his vessel is wholly submerged and entirely out of sight, for his greatest danger lies in the exposure of his upper search lights powerful enough to disclose him at a considerable distance—therefore when he is traveling on the surface the upper lights will be extinguished.

What I claim as new is:—

1. In a submarine chaser, a hull provided 70 with channels extending transversely with reference to the keel, illuminating means mounted within the channels, and directing their rays toward the bow and stern respectively, propelling and guiding means, and 75 submerging tanks located within the hull and extending across portions of the bottom thereof and upwardly along portions of the sides.

2. In a submarine chaser, the combination 80 with a double-conical hull, having rams at the bow and stern, and steering and propelling mechanisms; of arched headways at the top of the hull forward and rearward of its midlength, observation windows in the 85 end, sides, and top of each headway, searchlights contiguous to said windows, channels across the bottom of the hull, windows in the sides of the latter, searchlights within said channels, and other searchlights on the hull 90 near its rams and projecting their beams forward and rearward, these lights and those in the channels being always submerged.

3. In a submarine vessel of the type described, the combination with a hull having 95 a transverse channel across its bottom and an arched headway on its top, windows in the sides of the hull and headway and in the ends and top of said headway; of search lights carried at various points upon the 100 exterior of the hull and within said channel, and handles projecting from the searchlights to the interior for directing the beams of light from said searchlights.

In testimony whereof I affix my signature. 105
JOSEPH A. ARSENAULT.
